ROLLER SKATE

Alexander F. Kaptuller, Chicago, Ill., assignor
to Allied Engineering Company, Chicago, Ill.,
a corporation of Illinois

Application July 23, 1936, Serial No. 92,073

11 Claims. (Cl. 280—11.26)

My invention relates to roller skates and it has for its object the provision of a new and improved form and arrangement of parts by which a maximum of strength is provided by the use of a minimum amount of metal and whereby the manufacture, plating and assembly of the parts may be effected with the least trouble and expense.

It is one of the objects of my invention to provide an improved resilient mounting for the axle 10 by which the supporting wheels of the skate are connected with the framework, and to provide an improved arrangement of connecting means between the frame and the outside sleeve forming a part of such resilient mounting. It is another object of my invention to provide an improved arrangement of extension bar and associated parts by which the toe plate and the heel plate of the framework are adjustably connected together, whereby an easy adjustment may be effected and whereby great strength shall be provided by the use of a comparatively small amount of metal. More specifically, it is one of the objects of the invention to provide an improved arrangement of axle mounting means and its connection with the frame by means of brackets all arranged in combination with an extension bar which is adapted by cooperation with the brackets to serve effectively for extension purposes while serving automatically to hold the front and rear portions of the frame in the desired angular adjustment with respect to each other.

It is another object of my invention to provide an improved arrangement of bracket means by which a downwardly open channel is formed, the sheet metal forming the top wall of the channel being curved downwardly so as to close one end of the channel and serving thus to give the channel a high degree of strength with respect to transverse pressure thereon. Another object is to provide a channel as above specified with the wall portions in angular relationship to each other so as to enable an extension bar of similar shape to provide substantial transverse reinforcement, strengthening ribs being provided in the upper portions of the brackets merging at their lower ends into the walls of the channel.

It is a further object of my invention to improve devices of this type in sundry details hereinafter pointed out. The preferred means by which I have accomplished my several objects are illustrated in the accompanying drawings and are hereinafter specifically described. That which I believe to be new and desire to cover by Letters Patent is set forth in the claims.

In the drawings.—

Fig. 1 is a side view of the preferred form of my improved roller skate, with the near wheels removed and the corresponding portions of the axles broken away for clearness of illustration; 5

Fig. 2 is a rear end view of the skate as seen from the left in Fig. 1;

Fig. 3 is a front view of the skate as seen from the right in Fig. 1;

Fig. 4 is a horizontal sectional view taken at 10 line 4—4 of Fig. 1;

Fig. 5 is an enlarged vertical sectional view taken through the axle mounting means at one end of the skate, with parts broken away for clearness of illustration; 15

Fig. 6 is a view similar to Fig. 5 but showing the axle and its immediately associated parts removed representing an intermediate step in the assembly of the parts;

Fig. 7 is a perspective view of one of the brackets at the front end of the skate; 20

Fig. 8 is a perspective view of one of the brackets at the rear end of the skate; and

Fig. 9 is a vertical cross section on an enlarged scale taken at line 9—9 of Fig. 1. 25

Referring now to the several figures of the drawings in which corresponding parts are indicated by the same reference characters, 15 indicates the heel plate forming a part of the framework of the skate, being provided with an up-standing flange 16 as usual at its rear end portion and being provided with downwardly extending flanges 17 along its side edges, as is clearly shown in Fig. 2. The heel plate 15 is connected with supporting wheels 18 of any approved type 35 carried by an axle bolt 19 by means of suitable connecting parts as hereinafter described cooperating with brackets 20 and 21, as is clearly shown in Fig. 2.

The bracket 21 is shown in Fig. 8, the other bracket 20 being similar except that they are reversely formed for use at opposite sides. As shown in Fig. 8, the bracket 21 comprises a vertically disposed plate portion 22 having a transversely disposed flange portion 23 at its upper 40 edge. The two brackets 20 and 21 are secured to the bottom face of the transverse frame or heel plate 15, being securely welded at several places to the plate 15 and also to each other at points along the vertical plate or web portions 22 which 45 stand in face to face engagement with each other. At a distance below the flanges 23, each of the brackets is offset outwardly so as to provide a downwardly open channel portion 24 the top wall portions 25 at opposite sides of the channel pro- 50

55

viding outwardly facing shoulders, strengthening ribs 26 being pressed in the vertical plate or web portions 22 from the upper edges of such vertical plate portions and extending downwardly at an angle so as to merge into the top wall portions 25 as is clearly shown in Fig. 8. At their forward ends, the brackets are provided with overlapping lugs 27 and 28, see Fig. 9, which are effectively connected together as hereinafter described for reinforcing the structure. At their lower edges, each of the brackets 20 and 21 is provided with a downwardly extending arm 29 which is provided with a collar 30 formed integrally therewith, the two collars 30 of the two brackets being oppositely disposed in axially aligned position with respect to each other. Each of the brackets is provided at its lower edge with an inwardly extending flange 31 which is continued downwardly along the front face of the arm 29 to a point adjacent the collar 30.

At the forward end of the skate, a toe plate 32 is provided having downwardly extending flanges 33 along its side portions and a downwardly extending flange 34 across the front end. The transverse frame or toe plate 32 is supported by wheels 35 of any suitable type mounted upon an axle bolt 36 connected with the toe plate 32 by means as hereinafter described comprising brackets 37 and 38 as is best shown in Fig. 3.

30 The brackets 37 and 38 are arranged in general similarity to the brackets 20 and 21, the two brackets 37 and 38 being similar to each other except for reversed arrangement for enabling them to be used at opposite sides in cooperation with each other. As is best shown in Fig. 7, each of the brackets 37 and 38 comprises a vertically disposed plate portion 39 provided at its upper edge with a transversely disposed flange 40, the two brackets 37 and 38 being secured to the toe plate by means of the flanges 40 which are securely welded at various points to the bottom face of said plate 32, the vertical plate portions 39 of the two brackets being firmly secured together at a plurality of points preferably by welding.

45 Below the vertical plate portions 39, the two brackets are offset outwardly so as to provide a downwardly open channel, the top wall portion 41 of the channel at each side being disposed substantially parallel with the flange 40 and being braced strongly with respect thereto by means of ribs 42 pressed in the vertical plate portions 39 extending downwardly therein from the upper edge of the vertical plate portions and merging at their lower ends into the top plate portions 41.

55 As is best shown in Fig. 7, the top plate portion 41 of each of the brackets is curved downwardly at the forward end of the bracket so as to close the front end of the channel transversely serving thus to strengthen the channel formation greatly with respect to transverse pressure thereon, the curved shoulder portion by which the closure of the channel is effected being formed in a downwardly extending arm 43. At its lower end, the arm 43 of each of the brackets is provided with 60 an outwardly extending collar 44 formed integrally with the arm, the collars 44 of the two brackets being oppositely disposed in axial alignment with each other. At their rear ends, the bracket members 37 and 38 are provided with overlapping lugs 65 45 and 46 which are rigidly connected together by means of a bolt as hereinafter described, the bracket members being thus strongly reinforced with respect to each other.

70 The brackets 20 and 21 are further connected together by means of a metal sleeve 47 which is

inserted within the aligned collars 30 being secured firmly in position therein by means of spot-welding or in any other suitable manner. The sleeve 47 is preferably rolled out of flat stock and is provided at one end with an inwardly turned flange 48, as is clearly shown in Fig. 6, the opposite end of the sleeve 47 initially being left open in cylindrical form as shown in Fig. 6. In the formation of the skate, the transverse frame or heel plate 15, the brackets 20 and 21 and the sleeve 47 are first firmly secured together by spot-welding with the sleeve 47 in the condition shown in Fig. 6. The transverse frame or toe plate 32, the brackets 37 and 38, and a sleeve 47 such as that shown in Fig. 6 are likewise firmly secured together preferably by spot-welding with such sleeve 47 in position within the collars 44. The parts are then in condition for plating which is preferably effected at this stage of the assembly.

After the two units comprising the end portions of the framework are plated, each of the sleeves 47 is provided with an assembly such as that shown in Fig. 5 comprising a rubber sleeve 49 having an axle member 50 mounted therein also in the form of a sleeve having its middle portion expanded into the form of a ball as indicated at 51, the conformation of the rubber of the sleeve 49 being such that the rubber when held against radial expansion serves effectively for preventing the withdrawal of the axle member 50. The end portions of the sleeve 49 however are flared so as to enable the axle member 50 to have free swinging movement with respect to the sleeve 47 about the ball 51 as a fulcrum. The axle member 50 is preferably formed out of flat stock and is of a size to receive snugly the axle bolts 19 for mounting the wheels 18 in position thereon. After the sleeves 50 and 49 have been inserted into position within the sleeves 47, the end portions of the sleeves 47 are turned inwardly in the form of a flange 52 corresponding to the flange 48 above described, serving to prevent withdrawal of the rubber sleeve 49 from the sleeve 47.

For connecting the end portions of the framework of the skate, I have provided an extension bar 53 in the form of a downwardly open channel, the channel bar 53 being of a size and shape to fit snugly within the downwardly open channels of the brackets so as to hold the end portions of the framework in the desired alignment independently of the extension bar being fastened so as to prevent sliding movement thereof with respect to the channels of the framework. As is clearly shown in Fig. 9, the lower edges of the side portions of the channel bar 53 abut against the flanges 31 of the channel 24. In like manner the side portions of the bar 53 abut against inwardly extending flanges 37a formed on the lower edges of the brackets 37 and 38. The relation is such, by reason of the snug fit of the extension bar 53 within the channels of the framework, that the extension bar reinforces the framework strongly with respect to lateral pressure on the channel portions of the framework. The means for holding the extension bar from movement longitudinally with respect to the frame portions comprises two bolts 54 which extend through the overlapping lugs of the oppositely disposed brackets as above described and through openings 55 and 56 in the top wall of the extension bar 53, as is best shown in Fig. 4.

Front clamps 57 and 58 are preferably provided upon the toe plate 32, such clamps being in the usual angular form providing horizontally

disposed portions 59 which are slidably mounted in slideways provided on the toe plate, downwardly extending arm portions 60 of the clamps being adjustably connected together by means of the usual adjusting screw member 61 which has a bearing in notches 62 formed in the lower edge portions of the vertically disposed plates 38 of the brackets, as is clearly shown in Figs. 1 and 7. In the arrangement shown, the brackets are extended forwardly beyond the notches 62, being provided at their ends with outwardly extending flange portions 63 which are welded or otherwise firmly secured to the bottom face of the toe plate 32 for strengthening the frame construction.

By the use of my improved arrangement, I am enabled to form the parts of my improved skate very readily upon automatic machinery and am enabled very readily and rapidly to assemble the parts into the final form. The arrangement is such that the various parts reinforce each other so as to produce a maximum of strength by the use of a minimum amount of material whereby I am enabled to keep the weight of the finished skate down to a reasonable limit.

While I prefer to employ the form and arrangement of parts as shown in my drawings and as above described, it is to be understood that my invention is not limited thereto except so far as the narrower claims may be so limited in terms, it being understood that changes might well be made in the form and arrangement of the parts without departing from my invention.

35 I claim:—

1. In a roller skate, the combination of a transverse frame plate, two sheet metal brackets secured to the bottom face of said frame plate and having web portions extending downwardly therefrom opposite each other and secured together and portions below said web portions and offset outwardly with respect to each other, and then extending downwardly so as to provide in effect a downwardly open channel, an extension bar slidably mounted in said channel, and means rigidly connected with said brackets and extending across below said extension bar for supporting an axle transversely of the framework.

2. In a roller skate, the combination of a transverse frame plate, two sheet metal brackets secured to the bottom face of said frame plate and extending downwardly therefrom opposite each other and offset outwardly with respect to each other so as to provide in effect a downwardly open channel, an extension bar slidably mounted in said channel, transversely positioned and aligned collars on said brackets below said extension bar, and means for supporting an axle transversely of the framework from said collars comprising a sleeve mounting in said collars and rigidly secured thereto.

3. In a roller skate, the combination of two transverse frame plates, two pairs of sheet metal brackets secured to the bottom faces of said frame plates respectively with the brackets of each pair having portions extending downwardly opposite each other and secured together and portions therebelow offset outwardly with respect to each other so as to provide in effect a downwardly open channel, an extension bar slidably mounted in said channels serving to hold said transverse frame plates in substantial alignment with each other at adjusted positions apart, and means rigidly connected with the brackets of each of said pairs of brackets extending across below

said extension bar for supporting an axle transversely of the framework.

4. In a roller skate, the combination of two transverse frame plates, two pairs of sheet metal brackets secured to the bottom faces of said frame plates respectively with the brackets of each pair having portions extending downwardly opposite each other and secured together and portions therebelow offset outwardly with respect to each other so as to provide in effect a downwardly open channel, an extension bar in the form of a downwardly open channel member slidably mounted in said first named channels serving to hold said transverse frame plates in substantial alignment with each other at adjusted distances apart, and means rigidly connected with the brackets of each of said pairs of brackets extending across below said extension bar for supporting an axle transversely of the framework.

5. In a roller skate, the combination of two transverse frame plates, two pairs of sheet metal brackets secured to the bottom faces of said frame plates respectively with the brackets of each pair extending downwardly opposite each other and offset outwardly with respect to each other so as to provide in effect a downwardly open channel, an extension bar slidably mounted in said channels serving to hold said transverse frame plates in substantial alignment with each other at adjusted positions apart, transversely positioned and aligned collars on the brackets of each of said pairs of brackets below said extension bar, a sleeve rigidly secured in the collars of each pair of brackets, and means carried by said sleeves for supporting two axles in parallel position below said extension bar.

6. In a roller skate, the combination of a transverse frame plate, two sheet metal brackets secured to the bottom face of said frame plate and having portions extending downwardly therefrom opposite each other and secured together and portions therebelow offset outwardly with respect to each other so as to provide in effect a downwardly open channel, an extension bar slidably mounted in said channel, inwardly directed flanges on the lower edges of the side portions of said channel for holding said extension bar slidably in position, and means rigidly connected with said brackets and extending across below said extension bar for supporting an axle transversely of the framework.

7. In a roller skate, the combination of a transverse frame plate, two sheet metal brackets secured to the bottom face of said frame plate and extending downwardly therefrom opposite each other and offset outwardly with respect to each other so as to provide in effect a downwardly open channel, an extension bar slidably mounted in said channel, arms on said brackets extending downwardly below said extension bar, transversely positioned and aligned collars formed on said arms, inwardly directed flanges on the lower edges of the side portions of said channel and along the adjacent side edges of said arms serving by engagement with said extension bar to hold the bar slidably in position in the channel, a sleeve rigidly secured in said collars, and means carried by said sleeve for supporting an axle transversely of the framework.

8. In a roller skate, the combination of a transverse frame plate, two sheet metal brackets secured to the bottom face of said frame plate and extending downwardly therefrom opposite each other and offset outwardly with respect to each other so as to provide in effect a down-

- wardly open channel, transversely extending lugs carried by said brackets and overlapping each other, an extension bar slidably mounted in said channel, a bolt extending through openings in said lugs and said extension bar for securing the bar rigidly in position with respect to said brackets, and means rigidly connected with said brackets and extending across below said extension bar for supporting an axle transversely of the framework.
9. In a roller skate, the combination of a transverse frame plate, two sheet metal brackets secured to the bottom face of said frame plate and extending downwardly therefrom opposite each other and offset outwardly with respect to each other providing downwardly facing shoulders forming the top wall portion of a downwardly open channel, said shoulders being curved downwardly so as to close the channel at one end whereby the channel is substantially strengthened transversely, an extension bar slidably mounted in said channel, and means rigidly connected with said brackets and extending across below said extension bar for supporting an axle transversely of the framework.
10. In a roller skate, the combination of a transverse frame plate, two sheet metal brackets secured to the bottom face of said frame plate and extending downwardly therefrom opposite each other and offset outwardly with respect to each other providing downwardly facing shoulders forming the top wall portion of a downwardly open channel, each of said brackets having a strengthening rib pressed therein extending downwardly from the upper edge of the bracket and merging into said shoulder at its lower end, an extension bar slidably mounted in said channel, and means rigidly connected with said brackets and extending across below said extension bar for supporting an axle transversely of the framework.

ders forming the top wall portion of a downwardly open channel, said shoulders being curved downwardly so as to close the channel at one end whereby the channel is substantially strengthened transversely, each of said brackets having a strengthening rib pressed therein extending downwardly from the upper edge of the bracket and merging into said shoulder at its lower end, an extension bar slidably mounted in said channel, and means rigidly connected with said brackets and extending across below said extension bar for supporting an axle transversely of the framework.

11. In a roller skate, the combination of a transverse frame plate, two sheet metal brackets secured to the bottom face of said frame plate and extending downwardly therefrom opposite each other and offset outwardly with respect to each other providing downwardly facing shoulders forming the top wall portion of a downwardly open channel, each of said brackets having a strengthening rib pressed therein extending downwardly from the upper edge of the bracket and merging into said shoulder at its lower end, an extension bar slidably mounted in said channel and adapted to engage the wall portions of the channel, and means rigidly connected with said brackets and extending across below said extension bar for supporting an axle transversely of the framework.

ALEXANDER F. KAPTULLER.
